Primary Examiner — Jonathan J Han*Assistant Examiner* — Caitlin Mackenzie Williams(74) *Attorney, Agent, or Firm* — Greer, Burns & Crain, Ltd.(57) **CLAIM**

The ornamental design for a footwear upper and midsole, as shown and described.

DESCRIPTION

FIG. 1 is a front perspective view of a footwear upper and midsole showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The dot-dash broken lines depict the bounds of the claimed design and form no part thereof. The even dashed broken lines depict portions that form no part of the claimed design.

1 Claim, 7 Drawing Sheets(56)
